CLAIM

The ornamental design for the canning appliance, as shown and described.

DESCRIPTION

FIG. 1 is a top right front perspective view of the canning appliance;

FIG. 2 is a front view thereof;

FIG. 3 is a right side view thereof;

FIG. 4 is a rear view thereof;

FIG. 5 is a left side view thereof; and,

FIG. 6 is a top plan view thereof.

The broken lines in the drawings are for illustrative purposes only and form no part of the claimed design.
